CHAIR BACK CONSTRUCTION

Filed June 3, 1939

UNITED STATES PATENT OFFICE

2,243,811

CHAIR BACK CONSTRUCTION

James E. Bales, Aurora, Ill., assignor to Lyon Metal Products, Incorporated, Aurora, Ill., a corporation of Illinois

Application June 3, 1939, Serial No. 277,238

12 Claims. (Cl. 155—142)

This invention relates to chair constructions and more particularly to chairs formed of metal.

The present invention relates to an improved back construction for a metal chair, and among the objects of the present invention are to provide a metallic chair having a metallic backing constructed and arranged automatically to flex to fit the back of a person sitting in the chair; to provide a folding chair having a back which is substantially coextensive with the back of a person seated in the chair, and which back is adapted automatically to assume the proper back pitch relatively to the seat when the chair is opened for use; to provide a folding chair having an upstanding back frame and pivotally connected front and back legs, together with a seat pivotally connected to both of said front and back legs, and a chair back constructed and arranged quickly to be assembled and/or removed from said back frame and rear legs, easily and economically to be maintained in assembled position with respect thereto and which is not only capable of flexing to fit the back of a person seated in the chair but which has an automatically shiftable connection with a channel shaped portion of the rear legs which will permit the back in connection with such legs to shift relatively thereto when the chair is collapsed or opened for storage or for use, and wherein, when opening, the shiftable connection between the back and the rear legs is adapted adjustably to rock or shift to permit the back to have the proper back pitch; to provide a simple type of back comprising a lower horizontal cross piece and a plurality of vertically disposed, connecting, flexible strips and an upper connected cross piece, which latter piece is adapted detachably to fit within an upper channel portion of the main frame of the chair, and which lower cross piece is adapted detachably to slide within channeled portions of the rear legs; to provide a detachable and attachable back constructed and arranged to be quickly assembled in a standard type of channeled collapsible chair, and which back, when so assembled, will automatically flex and pivotally shift with respect to its mounting members to fit the back of a person seated in the chair, and whereby likewise to permit the chair to be collapsed, or unfolded for use; to provide, as an article of manufacture, a back capable of being constructed as a solid sheet back, perforated sheet back, horizontal strips, ladder type back, or other constructions, and adapted for attachment to channeled members of folding chairs, and which back extends substantially the full length of the back

of a person seated in the chair, to support the same, and which back, when connected to the frame members, is adapted to shift relatively to one of the leg members to permit the chair to fold and to assume proper back pitch when open; to provide these and other objects of invention as will be apparent from a perusal of the following specification when taken in connection with the accompanying drawing, wherein:

10 Fig. 1 is a perspective view of the improved back construction as applied to a type of chair forming the subject matter of a prior pending application;

15 Fig. 2 is a perspective view of the back as a separate article of manufacture;

Fig. 3 is a view in section taken on the line 3—3 of Fig. 1;

Fig. 4 is a sectional view showing the folded position of Fig. 3;

20 Fig. 5 is a detail sectional view taken on the line 5—5 of Fig. 1;

Fig. 6 is a detail sectional view taken on the line 6—6 of Fig. 1;

Fig. 7 is a detail sectional view taken on the line 7—7 of Fig. 3;

Fig. 8 is a detail view taken on the line 8—8 of Fig. 6; and

Figs. 9 and 10 are details of modifications.

In illustrating and describing the present invention, I have shown the chair as comprising a main chair construction like that described and claimed in the pending application of John B. O'Connor, Serial No. 170,256, filed October 21, 1937. However, it is to be understood that the mechanical features of the back, irrespective of the design of the back, may be utilized with other types of folding chair construction provided the same lend themselves to appropriate adaptation.

For the purposes of illustration I shall therefore describe the chair as applied to the specific construction referred to in the prior mentioned application, wherein the chair in general comprises a main frame formed from a metal channel bar 10, bent into substantially U-shape, and braced at its lower end by a cross brace 11. A pair of channel bars 12 and 13, connected by a cross brace 14, are pivotally secured at their upper ends to the channel bar 10 and together form a rear support frame for the chair. A seat 16 is pivotally secured to the main frame by pivots 17 and each rear corner of the seat is provided with a projection 18 carrying a cylindrical lug 19 slidable within its associated rear channel bar 12. Each of the channel bars carries a stop 20 for limiting the upward movement of its as-

sociated lug. The lower ends of the channel bars carry rubber feet 21 affording a firm and solid supporting construction.

By virtue of the foregoing construction it will be seen that the chair is of the folding type and may be readily manipulated from its open or seating position, as shown in Figs. 1 and 3, to its closed position, as shown in Fig. 4, for storage purposes. This operation may be readily effected by grasping the chair back and front of the seat and rotating the seat clockwise with respect to the frame about the pivots 17. During this operation the rear support frame comprising the channels 12 and 13 will be moved into substantial engagement with the main frame channel 16, and the seat will simultaneously be brought into the plane of the main frame whereby to collapse the chair construction. When it is desired again to open the chair to seating position, the seat is pivoted counterclockwise with respect to the frame, bringing the parts into the position illustrated in Fig. 1. During this operation the stops 20 limit the upward movement of the rear of the seat, thus holding the seat during use in firm, substantially horizontal position and against collapse.

Inasmuch as the details of the construction of the seat are fully shown and claimed in the prior mentioned application of John B. O'Connor, Serial No. 170,256, no further description thereof is necessary. The aforementioned construction is claimed in the prior mentioned case. The main features of the present invention reside in the construction of the back, as shown in Fig. 2, and particularly in the functional cooperation of this back with the channel members 10 and 12 hereinafter described.

The back of the present invention is constructed substantially of full length, whereby to support the entire back, including the small of the back, of the person seated in the chair, and in a manner such that the support will be a flexible one, automatically adjusting itself to the particular conformation of the seated person, and in such a manner that the mounting of the lower portion of the back rest may shift automatically with respect to the channel member 12 not only in the open position of the chair, as when a person sits therein, but also when the chair is collapsed to folded position. In addition, the back is constructed so that it may quickly be removed or applied to the frame construction hereinbefore described, in the most expeditious and economical manner. Furthermore, the back is constructed of simple sheet metal parts, providing maximum flexibility combined with requisite rigidity and support, and providing in addition a most ornate, simple and pleasing appearance.

Referring to the back construction, the same comprises a lower cross brace 22 formed of sheet metal doubled upon itself in the manner illustrated in section in Fig. 6, and an upper cross member 24 of sheet metal and generally of U-shape in cross section, as shown clearly in Fig. 5. This member 24 is shorter on its upper surface, as at 26, than it is on its lower surface, and is formed slightly beveled at its upper ends, as at 28 and 30, to fit within the rounded upper portion of the channel member 10. At desired spaced points the channel U-shape member 24 is slotted, as at 32, to receive the bent ends of a plurality of vertically disposed, flexible, metal backing strips 34, the bottom ends of which pass through suitable spaced slots 36 in the folded

bottom cross strip 22. Rivets 38 hold these strips connected to the cross strip 22 and serve to assist in maintaining the folds of the cross strip together. Each one of the vertical strips 34 is formed as a single strip of flexible spring metal.

Means is provided for adjustably, pivotally and shiftably uniting the lower cross bar 22 within the channel of the member 12, whereby the member 22 may shift with relation to the channel members 12 and 13. The specific means illustrated for this purpose comprises a cam-like member 40 formed of sheet metal and centrally slotted to permit each end 42 of the bar 22 to pass therethrough and to be bent thereover and welded thereto, as shown in Fig. 8. In addition, the ends 44 and 46 are bent in the manner shown in cross section in Fig. 8, so as to provide a minimum of resistance to movement of the ends relative to the channel shape leg members 12 and 13. In addition the opposite sides of these cam members 40 are slightly tapered in reverse directions from a central, substantially rounded portion, as shown at 48 and 50, whereby to provide opposed rocking faces for the ends of the bar 22 so that the bar may rock on these surfaces 48 and 50 against the channel walls of the legs 12 and 13. In addition, by means of a screw 52, the upper cross bar 26 may detachably be held within the upper portion of the channel frame member 10.

Referring now particularly to the cooperation of the back construction with the general features of the chair frame, and particularly to Figs. 4 and 6, it will be noted that when the chair is moved from collapsed, closed position, as shown in Fig. 4, to the open position shown in Fig. 3, during the opening movement the cam-shaped members 40 will have rocked in the channel shaped members 12 and 13 from the position shown in Fig. 4 to the position shown in Fig. 3, the rocking taking place about the points 48 and 50 on the sides of the channel. It will also be noted that the members 40 will slide downwardly in the channel shaped leg members 12 and 13 to accommodate the opening movement of the legs. Conversely, when the chair is moved from open position to collapsed position, a substantially opposite rocking and sliding movement of the lugs 40 on the lower cross piece 22 will take place. When a person sits on the seat of the chair, when in the open position shown in Fig. 1, no rocking of the lug members 40 in the channel shaped bar 22 will take place. However, it is at this instant that the flexibility of the vertical back strips 34 functions. By reference to Fig. 6, it will be noted that these strips, being of spring metal and being attached only at top and bottom, will be free to bow outwardly to accommodate themselves to the particular back conformation of the person sitting on the chair seat, so that the back of such person will be flexibly and resiliently supported throughout the entire length of the back. Furthermore it will be noted that the lower cross support 22, being held within the channel walls of the leg supports 12 and 13, will form a support for the back of the hips of the person seated and will not permit them to bulge out rearwardly beyond the rear edge of the seat 16. Also, when the seat is in open position, this lower cross brace 22 will be substantially in the same vertical plane with the rear edge of the seat, and the vertical strips 34 will extend in a general backwardly slanting position to the point where they connect

with the upper cross brace 24 which is detachably confined within the horizontal channel portion of the main frame 10.

It will thus be seen that I have provided a chair wherein the back is attached to the stationary top portion of the channel shaped member 10 and is likewise attached to the rear legs 12 and 13, which legs are pivotally and foldably connected to the frame member 10 and provide a connection which permits of shifting movement to allow the chair to be opened or closed, and wherein, in open position, the back will flexibly support and conform to the back of the person seated in the chair. Furthermore, in such a construction the back construction permits the seat snugly to fit in a substantially vertical and parallel plane with the main frame 10 and the leg portions 12 and 13, whereby the chair occupies a minimum of space. This is due to the fact that the cross bar 22 is not centrally disposed with respect to the lugs 40 but is disposed slightly to the rear thereof, as shown in Fig. 6.

In Figures 9 and 10 I have shown modifications of the construction for attaching the vertical ribs 34 to the channel piece 24. In Fig. 9 the upper end of the ribs 34 are riveted to the side of the channel piece 24, the channel piece 24 being made of smaller lateral cross-section to fit snugly within the channel member 10 of the chair frame. In Fig. 10 the cross member 24 is slotted at spaced-apart points along its bottom to receive therein the top ends of the strips 34 which are riveted to the side member much as in the manner shown in Fig. 9.

The invention is hereby claimed as follows:

1. A folding chair comprising a substantially U-shape frame, the lower portions of which form front legs, rear legs pivoted to said main frame, a seat pivoted to said frame and shiftably connected to said rear legs, and a full-length back being attached to the central portion of the U-shape frame and including a cross brace fixed to the lower ends of the flexible members, means shiftably connecting said cross brace rearwardly of the longitudinal center of the rear legs whereby when the chair is folded the cross brace will clear a rearwardly projected portion.

2. A folding chair comprising a main frame adapted in open position to extend diagonally rearwardly in upright position, comprising front legs, a pair of rear legs pivotally connected to said main frame substantially intermediate its vertical length, a seat of curved contour pivotally connected to said front legs and shiftably connected to said rear legs and adapted to collapse and open with respect thereto, and a back extending from the top of said main frame downwardly and having its lower portion located adjacent the upper surface of the rear of the seat when the chair is in open position, said back being attached to the upper portion of said main frame and including a cross brace, means shiftably connecting said cross brace rearwardly of the longitudinal center of the rear legs whereby when the chair is folded the cross brace will clear a rearwardly projected portion.

3. A folding chair comprising an inverted U-shape frame, the lower portions of which form front legs and the upper portion of which forms a back frame, a pair of rear legs pivotally connected to the upper portion of said first frame, a seat pivotally connected to said frame and shiftably connected to said legs, said main frame

and legs being of channel shape construction, a sheet metal upper strip bent to U-shape sectional construction adapted to nest within the channel of the upper portion of the main frame, said strip having spaced slots therein, a plurality of spaced apart spring metal strips, each having an end in a slot in the upper strip, said end being fastened within said upper strip, and a lower cross brace suitably slotted and having the lower ends of said spring metal strips disposed and fastened therein, said lower cross brace having a sheet metal lug attached at each end, each of said sheet metal lugs being slidably disposed in a channel of a rear leg member, said lower cross brace, when the chair is in open position, lying substantially adjacent the upper surface of the rear of the seat, and said spring metal strips providing a substantially full length back for the chair.

4. In combination, a substantially inverted U-shape member of channel shaped construction, the bottom portions forming legs, a lower brace interconnecting said legs, a pair of rear legs pivotally connected to the upper portion of said main frame, said legs being of channel shaped construction, a brace interconnecting said rear legs, a chair seat pivoted to said main frame and shiftably connected to said rear legs, a plurality of spaced apart, vertically extending spring metal strips having their upper ends connected to the horizontal length of the inverted U-shape frame member, a lower cross brace connected to the lower ends of said spring metal strips, and a pair of sheet metal lugs each having an aperture disposed rearwardly of the center of said lug, said cross brace having its end projecting through said aperture and fastened to said lug, said lug having its central portion provided with opposed substantially rounded portions and tapering toward each end to provide converging faces at each side thereof, each of said lugs being disposed in a channel of a leg whereby to permit said lugs and said lower cross member to slide longitudinally of said leg channel and to rock therein during the opening and closing movement of the legs and the seat.

5. A seat back adapted for attachment to the frame member and legs of a folding chair, comprising a sheet metal upper cross brace of substantially U-shape cross section having tapered upper surfaces adapted for insertion in the channeled horizontal reach of the main inverted U-shape frame member of the chair and provided with spaced apart slots therein, a plurality of spring metal elongated vertically extending strips, each having an end disposed in a slot, with the end bent within said cross brace and fastened thereto, a lower cross piece of sheet metal suitably slotted, each slot adapted to receive the lower end of a spring metal strip, and means for fastening such ends thereto, the opposed ends of the lower cross piece having fastened thereto a substantially diamond shaped lug, the corners of the lug being rounded to provide cam shaped faces to permit rocking and sliding movement of the lugs within the channeled leg portions of a folding chair.

6. A seat back adapted for attachment to the frame members and legs of a folding chair, comprising a sheet metal upper cross brace of substantially U-shape cross section having tapered upper surfaces adapted for insertion in the channeled horizontal reach of the main inverted U-shape frame member of the chair and provided with spaced apart slots therein, a plurality of

spring metal elongated vertically extending strips, each having an end disposed in a slot, with the end bent within said cross brace and fastened thereto, a lower cross piece of sheet metal suitably slotted, each slot adapted to receive the lower end of a spring metal strip, and means for fastening such ends thereto, the opposed ends of the lower cross piece having fastened thereto a substantially diamond shaped lug, the corners of the lug being rounded to provide cam shaped faces to permit rocking and sliding movement of the lugs within the channeled leg portions of a folding chair, said lug portions being formed of sheet metal and having their opposed ends acutely bent to provide sliding surfaces presenting a minimum of friction.

7. A chair back comprising an upper cross member of substantially U-shape cross section having its upper opposed ends beveled, the lower portion of the channel shaped member along its length being provided with a plurality of spaced slots, a plurality of relatively long spring metal strips, each strip having its upper end passing through one of the slots and lying within the U-shape cross member and suitably connected thereto, a lower cross piece comprising a sheet metal strip bent upon itself and suitably slotted, each slot to receive the lower end of a spring metal strip, there being means for suitably connecting the same within the lower cross piece, each end of the lower cross piece having a sheet metal lug, said lug being substantially diamond shaped, the acute angles of the diamond shape being rounded to provide a central thickened rocking portion and opposed pairs of diagonally disposed faces, each end of the lower cross piece passing through a slot in the lug and fastened thereto, said slot in the lug being laterally of the central longitudinal axis of the lug.

8. A folding chair comprising a main frame forming a back frame and front legs, a pair of rear legs each pivotally connected to the upper portion of the main frame, a seat of curved contour pivotally connected to the main frame and shiftably connected to the rear legs whereby to permit said legs and seat to collapse to adjacent folded position, and a full length back for said chair attached to the upper portion of the main frame and attached to the opposed rear legs adjacent the rear edge of the seat, said last mentioned attachment being shiftable to permit the opening and closing movement of the legs and seat and including a cross brace, means shiftably connecting said cross brace rearwardly of the longitudinal center of the rear legs whereby when the chair is folded the cross brace will clear a rearwardly projected portion of the seat.

9. A folding chair comprising a main frame forming an upper back frame and front legs, a pair of rear legs pivoted to the upper portion of said back frame, a chair seat pivotally connected to said main frame and shiftably connected to said rear legs whereby said seat and legs are adapted to collapse or to be opened, the seating surface of said seat extending rearwardly substantially to the rear legs in open position, a full-length back for said back frame and rear legs.

said back comprising a plurality of relatively long, spaced-apart, spring metal strips and being attached to the upper portion of said upper frame, and means for slidably and rockably connecting

5 said back to said rear legs, and including a cross brace, said spring metal strips being connected to the brace at their lower ends, means shiftably rockably connecting said cross brace rearwardly of the longitudinal center of the rear legs where-
10 by when the chair is folded the cross brace will clear a rearwardly projected portion of the seat.

10. A seat back adapted for attachment to the frame member and legs of a folding chair comprising a plurality of spring metal, elongated, vertically extending strips, a lower cross brace, and a substantially diamond-shaped lug on each of the opposed ends of said lower cross brace, the lower ends of said spring metal strips being secured in spaced-apart relation to said lower cross brace, and the corners of said lugs being rounded to provide cam-shaped faces to permit rocking and sliding movement of the lugs within the channeled leg portions of a folding chair.

11. A seat back adapted for attachment to the frame member and legs of a folding chair comprising a plurality of spring metal, elongated, vertically extending strips, a lower cross brace, and a substantially diamond-shaped lug on each of the opposed ends of said lower cross brace, the lower ends of said spring metal strips being secured in spaced-apart relation to said lower cross brace, said lower cross brace being located laterally rearwardly of the central longitudinal axis of said lugs, and the corners of said lugs being rounded to provide cam-shaped faces to permit rocking and sliding movement of the lugs within the channeled leg portions of a folding chair.

the channelled leg portions of a folding chair.

12. A folding chair comprising a main frame, the lower portions of which form front legs for the chair, said main frame extending diagonally upwardly and rearwardly, a pair of channel-shaped legs pivotally connected to said main frame slightly above the central portion of said main frame, a seat pivotally connected to said front legs and shiftably connected to said rear legs, said legs and seat being adapted to collapse into juxtaposition and substantially into a single plane, a back comprising a plurality of spring metal, elongated, vertically extending strips secured at their upper ends in spaced relation to said main frame and at their lower ends in spaced relation to a lower cross brace, a substantially diamond-shaped lug on each of the opposed ends of said lower cross brace, said lugs being slidably disposed in the channels of the rear leg members and the corners of said lugs being rounded to provide cam-shaped faces to permit rocking and sliding movement of the lugs within the channeled rear leg members, said lugs being formed of sheet metal and having their opposed ends acutely bent to provide sliding surfaces pressing against the inner faces of the channelled leg portions and presenting a minimum of friction producing surface against said channelled leg portions.

JAMES E. BALES
